UNITED STATES PATENT OFFICE.

EDMUND ULRICH STEINER, OF BROOKLYN, NEW YORK.

WALKING DOLL.

SPECIFICATION forming part of Letters Patent No. 695,121, dated March 11, 1902.

Application filed June 8, 1901. Serial No. 63,691. (No model.)

To all whom it may concern:

Be it known that I, EDMUND ULRICH STEINER, a citizen of the United States of America, and a resident of the borough of Brooklyn, 5 New York, county of Kings, State of New York, have invented certain new and useful Improvements in Walking Dolls, of which the following is a specification.

My invention relates to toy figures, particularly dolls and the like, which are purposed to imitate automatically the motion of walking. It is the special object of this invention to produce a walking doll of that type which when led by the hands, for instance, 10 will move its feet forward alternately and successively. The walking doll further is constructed so that it may be made to sit erectly. In order to produce a commercially-successful toy of this type, the mechanism 15 employed therein must be simple, cheap, and practically indestructible. These requirements are fulfilled in my novel walking doll, which has a very plain mechanism, so that it can be manufactured cheaply and still is very 20 durable.

The invention is illustrated in the accompanying drawings, in which—

Figure 1 is a front elevation of the undressed doll embodying my invention and 25 showing the middle portion broken away. Fig. 2 is a cross-section on line $x-x$ of Fig. 1, showing in bottom view a horizontal reciprocating movement. Fig. 3 represents in section the lower right portion of the body on line $y-y$, and Fig. 4 shows in side view one leg 30 of the doll turned up rectangularly in the position in which it rests when the doll is made to sit erectly.

Similar letters of reference denote like parts 35 in all the figures.

The body and the legs of the doll are made separate and connected by parts of the mechanism. The leg-actuating mechanism is contained in the lower hollow portion of the 40 trunk of the body, and consists, essentially, in a horizontal reciprocating movement which possesses the advantage of not extending high up into the hollow trunk, and therefore is easily mounted therein. The mechanism is 45 preferably made of metal and consists of a frame f , Fig. 1, whose top portion forms a horizontal bar and is bent on both sides rec-

tangularly downward, forming two side bars b . Between the extreme ends of b there is secured a rod r , which is surrounded closely 55 by a tube r' , divided into two halves $r^2 r^3$. On each of these sliding halves $r^2 r^3$ is movably fastened a shank s . Each shank extends down into one leg and is secured to same, so that it is thereby connected to the mechanism. 60 The halves $r^2 r^3$ of the tube r' carry each one shank s , so that r^2 moves slightly on the rod r with one shank and leg, while r^3 moves slightly with the other shank and leg. The horizontal top portion of the frame f carries 65 on its lower surface the oscillating lever l , Figs. 1 and 2. This lever is centrally pivoted to the frame, permitting thus of its to-and-fro motion in a horizontal plane. The central portion of the lever slides or moves on 70 the lower surface of the top portion of the frame. Then the lever is bent vertically down on both sides and again horizontally, so that its side ends are parallel with the top portion of the frame, as at l . Each shank is gradually increasing in width from bottom to top, 75 as is shown in Fig. 3, and at the top the central portion is cut out, so that two vertical stops $s' s'$ are produced on its side ends. In the center of the cut-out portion there is produced a square incision i , Fig. 3, in which 80 rests the one side portion l' of the oscillating lever l , while in the incision of the other shank rests the other side portion of the lever l . The top portion of the frame, Fig. 2, is provided with four recesses e , in which the stops s' rest alternately when the doll is walking, 85 arresting thereby the motion of the legs at a certain point, so that the doll can only make graceful steps of a certain length. After this 90 mechanism has been secured to the legs then it is mounted within the lower portion of the hollow trunk of the body and secured therein by means of a cement, which adheres both to the composition of the trunk and the metal, 95 or it may be riveted.

If now the doll is desired to walk, the child takes it by the hands, drawing it gently forward while standing on one foot. Then the shank above this foot moves on the rod r , actuating thereby the oscillating lever l in a horizontal plane, whereby the other shank is moved by means of the other portion l' , which consequently moves the other leg forward.

In order to enable the doll to sit, the lower portion of each shank *s* is pivoted to the metal bar *b'*, Fig. 1, which extends somewhat down into the leg. At the extreme end of *b'* a spring *s'* is riveted thereto. This spring is curved and extends upward to the end of the bar *b'*, where its end rests against a small detent *d*, contained in an opening on the end of the bar *b'* and ending in an opening in the shank which coincides with the opening in the *b'*. By turning up the legs on the pivots *r'*, which connect the shanks *s* with the bars *b'*, until they form a right angle with the body then each detent will move out of the opening in each shank and finally rest against the horizontal rear end of same. The spring *s'*, pressing against the head of the detent, prevents it from falling out.

It is plainly seen that the legs and the shanks are perfectly secured when the detent is in the opening in the shank.

In the described manner, an automatic walking doll is produced which works by means of a very plain reciprocating-lever mechanism that moves in a horizontal plane, and in addition the doll may be made to sit erectly.

Having thus described my invention, I claim as new and desire to secure by Letters Patent—

1. In a walking mechanism for toy figures the combination with the body, of a frame mounted therein composed of a U-shaped bar, a horizontally-oscillating lever loosely connected with the bar and provided with offset horizontal ends, a rod connecting the ends of the bar, sleeves mounted thereon, bifurcated

shanks rigidly secured to the sleeves and extending into engagement at one end with the limbs of the figure, and their bifurcated ends actuating the lever and adapted to engage the bar to limit the movement of the limbs, substantially as specified.

2. In a doll of the class described the combination of a frame mounted in the body, and having shanks pivotally connected therewith, plates mounted in the limbs of the figure and pivotally connected to the shanks, a spring-pressed detent carried by the plates and adapted to be engaged and disengaged from the shanks when it is desired to have the figure assume an upright or sitting position.

3. In a walking mechanism for toy figures a frame forming a horizontal bar at the top provided with four recesses and two sides rectangular thereto, and a rod connecting the bottom ends of the sides, a slidable tube surrounding closely the rod and divided in the center, an oscillating lever pivoted centrally to the inner surface of the top frame-bar bent downward on both sides near the pivot and again rectangular and parallel to the top bar of the frame and rod, and two shanks secured one on each half of the slidable tube extending in width from bottom to top and provided with an incision in the center engaging the lever, and two stops at the top ends coinciding with the recesses, as specified.

Signed by me at New York, State of New York, this 28th day of May, 1901.

EDMUND ULRICH STEINER.
